Primary Examiner — Mary Ann Calabrese

(57) **CLAIM**

The ornamental design for a makeup mirror, as shown and described.

DESCRIPTION

FIG. 1 is a front perspective view of a makeup mirror showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of the makeup mirror where the makeup mirror is in an alternate configuration of use; and,

FIG. 10 is an enlarged detailed view of the encircled area 10 shown in FIG. 1.

The broken lines in the drawings depict portions of the makeup mirror that form no part of the claimed design.

1 Claim, 10 Drawing Sheets
